The ornamental design for the bendable arm, as shown and described.

DESCRIPTION

FIG. 1 shows a front perspective view of a bendable arm; FIG. 2 shows a front view of the bendable arm of FIG. 1; FIG. 3 shows a rear view of the bendable arm of FIG. 1; FIG. 4 shows left side view of the bendable arm of FIG. 1; FIG. 5 shows a right side view of the bendable arm of FIG. 1;

FIG. 6 shows a bottom view of the bendable arm of FIG. 1; and,

FIG. 7 shows a top view of the bendable arm of FIG. 1. The broken lines in the FIGS. 1-7 illustrate portions of the bendable arm which form no part of the claimed design.
